2,253,122

INK CIRCULATING MECHANISM

Edward William Hamant, Dayton, Ohio, assignor
to Oxford Varnish Corporation, Detroit, Mich.,
a corporation of Michigan

Original application September 3, 1937, Serial No.
162,264. Divided and this application August
18, 1939, Serial No. 290,820

6 Claims. (Cl. 101—154)

This invention relates to an inking system for a surface decorating mechanism and especially an apparatus or mechanism for circulating and re-circulating ink, pigment or graining paste in a surface decorating or graining mechanism.

The present application is a division of my application resulting in issuance of Pat. 2,170,817 dated August 29, 1939.

The general object of the present invention is to provide an improved ink or pigment circulating apparatus for circulating ink or pigment in a surface decorating mechanism such as, for instance, a graining machine.

Another object of the present invention is to provide an improved apparatus for circulating ink or pigment in a surface decorating machine, together with an improved operating mechanism therefor, which will be simple to manufacture, efficient in operation, readily adapted for use with various types of surface decorating machines, and quickly adjusted to suit the printing mechanism and operating conditions with which it is used.

Other objects of the invention will become more apparent from the following description, reference being had to the accompanying drawing, in which there is shown a preferred embodiment of the invention. The essential features of the invention will be summarized in the claims.

In the drawing, Fig. 1 is a side elevation of a portion of a decorating mechanism, illustrating my improved ink circulating mechanism in position thereon, and Fig. 2 is a vertical axial section taken through the circulating mechanism, the plane of the section being substantially parallel with Fig. 1.

The pigment or ink circulating mechanism with which this invention is particularly concerned, is illustrated in the drawing as applied to a surface decorating machine of the type illustrated and claimed in Patent No. 2,096,731, issued to my assignee, Oxford Varnish Corporation, October 26, 1937. This decorating mechanism is especially adapted for the application of a decorative coating to the surfaces of metallic frames, such as sheet-metal automotive vehicle window frames and the like, by an offset printing process. However, it will become obvious that the present invention may be used with many other types of surface decorating mechanisms.

The surface decorating mechanism shown in the drawing comprises a pattern cylinder 10, having mounted thereon a pattern 11. The pattern may be an intaglio printing plate or cylinder having a continuous design etched therein.

A coating of ink or graining paste is applied to the pattern and is forced into the depressions therein. The excess ink or paste is then removed by a suitable scraping mechanism such as that 5 illustrated, described and claimed in my co-pending application for Letters Patent heretofore referred to. Suffice it to say that this scraping mechanism leaves only such pigment on the pattern as remains in the depressions in the plate, and removes the surplus, permitting it to fall by gravity to a trough or pan 21 beneath the pattern roll.

Mounted adjacent to and in running contact with the pattern roll 10 is an offset or transfer roll 15. This transfer roll may be made of the usual glue and glycerin compound, or any other suitable material which will cause the ink in the depressions of the pattern plate to be transferred therefrom to the surface of such transfer roll, 20 and then transfer such ink to the work W. The pattern roll 10 and the transfer roll 15 are mounted on respective shafts 18 and 20, which are suitably journaled in frame members 21.

Ink is applied to the pattern 11 by an applicator 25 such as that shown and described in Patent No. 1,997,612, issued to my assignee, Oxford Varnish Corporation, April 16, 1935, and reference to such patent may be had for a detailed description of such mechanism. Briefly, such ink applying 30 mechanism comprises a tube 30 which extends parallel with the axis of the pattern roll 10. A conveyor screw 31 is rotatably mounted within this tube. The lower end of the tube is arranged to project into a reservoir or receptacle 33, and 35 is provided with a suitable opening 34 to permit ink to be drawn upwardly by the screw from the reservoir. The tube 30 is positioned adjacent and parallel with the surface of the pattern 11, as indicated in Fig. 1. Thus ink drawn upwardly 40 from the reservoir is fed to the pattern roll through a port or opening 35 in the wall of the tube 30, and falls downwardly along the pattern.

The rolls and ink applicator are all power driven. As illustrated, the pattern roll shaft 18 and the transfer roll shaft 20 are provided with interengaging gears 22 and 23, respectively. The pattern roll shaft is driven by a power shaft 24 through suitable gearing 25. Secured to the upper end of the ink applicator screw 31 is a pinion 26, which meshes with the pattern roll gear 22. Thus, the various mechanisms are driven in synchronization with each other.

The ink or graining paste applied to the pattern 11 by the ink applicator is spread thereon 55 and the excess ink or paste removed by a suit-

able scraper mechanism, not shown in this application. However, reference may be had to Patent 2,170,817, heretofore referred to, for a complete description of such scraper mechanism. Such mechanism causes the excess ink removed thereby, to fall by gravity onto an inclined surface 27 of the frame 21 and thence through a passageway 28, into a pan or receptacle 29, which is supported beneath and by the frame 21 in any suitable manner. From the receptacle 29, the ink is returned to the reservoir 33 by the recirculating mechanism with which the present invention is particularly concerned.

The ink or pigment recirculating mechanism includes a pump 100 and is best illustrated in Fig. 2. As there shown, this pump comprises a pair of telescopically arranged tubes 40 and 41. The upper tube 40 is adjustably secured by a set screw 42 to a block 43 which is removably carried by the frame 21. Projecting into and secured to the upper end of the tube 40 as by welding is a third tube 44, to which a conduit 45 is secured in any suitable manner to conduct the ink from the pump to the reservoir 33. The lower end of the tube 40 is peened inwardly, as indicated at 48, and is normally closed by a ball 49, which is slightly less in diameter than the internal diameter of the tube 40. A spring 50 interposed between the lower end of the tube 44 and the ball 49 normally maintains the ball in its lowermost or tube closing position.

The lower pump tube 41 slidably embraces the tube 40 and its lower end is peened inwardly as at 51 and is normally closed by a ball 52, the diameter of which is less than the internal diameter of the tube 41. A spring 53, interposed between the lower end of the tube 40 and the ball 52, normally maintains the ball in its lowermost or tube closing position. When the tube 41 is raised relative to the tube 40, ink trapped between the two balls 49 and 52 forces the ball 49 upward against the action of the spring 50 and the trapped ink is forced into the tube 40. When the tube 41 is moved downward relative to the tube 40, the spring 50 causes the ball 49 to close the passageway between the tubes 40 and 41, and creates a partial vacuum in the tube 41. When, however, the ball 52, of the tube 41, engages the bottom wall 54 of the pan or receptacle, 29, it is moved upward against the action of its spring 53 and the partial vacuum in the tube 41 causes the ink in such pan to flow into such tube. Thus, it will be seen that constant reciprocation of the tube 41 relative to the tube 40 will cause the ink to be drawn upward from the pan 29 and returned to the reservoir 33.

The pump tube 41 is reciprocated by a cam 60 which is secured to the lower end of the pattern roll shaft 18 beneath the frame 21. As illustrated in the drawing, the tube 41 is connected by a link 62 with one arm 63 of a bell crank, the other arm 64 of which is provided with a roller 65. The roller 65 is maintained in contact with the cam 60 by a spring 66 interposed between the bell crank arm 63 and the pump supporting bracket 43, which as heretofore mentioned is removably secured to the frame 21.

From the foregoing description it will be seen that there is provided a compact ink recirculating mechanism which may be removed from the decorating mechanism as a unit, and which may be cleansed or adjusted readily, thereby facilitating the change of colors. Further, such mechanism may be economically manufactured and applied to a decorating apparatus.

I claim:

1. A circulating mechanism for circulating ink graining paste and the like comprising a receptacle adapted to receive a supply of such ink, graining paste or the like, a pump mounted in said receptacle and having a reciprocable member provided with an intake valve, means to move said member to bring said valve into contact with said receptacle at a point beneath the ink level thereof, and wherein said valve is arranged and adapted to open automatically consequent upon the engagement of said valve with said receptacle.

15 2. A circulating mechanism for circulating ink graining paste and the like comprising a receptacle adapted to receive a supply of such ink, graining paste or the like, a pump mounted in said receptacle and having a reciprocable member provided with an intake valve, means to alternately move said member to bring said valve into and out of contact with said receptacle at a point beneath the ink level thereof, said valve being arranged and adapted to open automatically consequent upon its engagement with said receptacle and wherein the movement of said member produces a partial vacuum in said pump whereby such ink, graining paste or the like will be drawn into said pump.

20 3. A circulating mechanism for circulating ink graining paste and the like comprising a receptacle adapted to receive a supply of ink, graining paste or the like, a pump mounted in said receptacle, said pump including a reciprocable member provided with an intake valve, means to move said member to bring said valve into and out of contact with the bottom of said receptacle, said valve being arranged and adapted to open automatically consequent upon its engagement with the bottom of said receptacle, and wherein the movement of said member toward the bottom of said receptacle produces a partial vacuum in said pump whereby ink, graining paste or the like will be drawn into said pump consequent upon the opening of said valve, and means whereby the movement of said member in the opposite direction discharges such ink, graining paste or the like from said pump.

25 4. A circulating mechanism for ink, graining paste and the like, comprising a pair of telescopically arranged tubes, one extending below the other, a check valve in the lower end of each tube, resilient means within respective tubes to maintain said respective check valves in a normal or closed position, the check valve in the lowermost tube comprising a ball which extends below the lowermost surface of said tube and which is adapted to permit flow of material into said tube when said ball is forced upward into said tube as by contact with an external object, and means to reciprocate the lowermost tube relative to the other tube.

30 5. A circulating mechanism for circulating ink, graining paste and the like, said mechanism comprising a tube, a check valve at the lower end of said tube to prevent flow of material from such end of said tube, a second tube telescopically and slidably embracing the first tube, said second tube extending beyond the end of the first tube, a check valve normally closing the extending end of said second tube, resilient means normally acting to maintain said check in a closed position, wherein said check valve extends beyond the end of said last named tube and is arranged and adapted to be automatically opened consequent upon striking an external surface,

and means to reciprocate said second named tube relative to the first named tube to cause such contact to take place.

6. A circulating mechanism for circulating fluids or semi-fluids, such as ink, graining paste and the like, said mechanism comprising a tube, a ball check valve at the lower end of said tube to prevent flow of material from such end of said tube, a spring in said tube to close said check valve, a second tube telescopically and slidably embracing the first tube, said second tube extending below the lowermost end of the first tube, a ball check valve normally closing the extending end of said second tube, a spring interposed between the end of the first tube and 15

the ball check normally acting to maintain said ball check in a closed position, and said tubes in an expanded position, the ball of said last-named check valve extending beyond the lowermost end of said last-named tube whereby when it contacts the bottom of a receptacle containing the fluid or semi-fluid said last-named check will be automatically opened to admit fluid to said tube, and means to reciprocate said second-named tube relative to the first-named tube and the bottom of the receptacle to cause such contact to take place and to subsequently move the second-named tube toward the first-named tube to discharge the fluid from the pump.

EDWARD WILLIAM HAMANT.
